Sherman S. Jewett & Francis H. Root, of Buffalo, N.Y.
Letters Patent No. 1095. Dated April 26, 1859.

The schedule referred to in these Letters Patent and making part of the same. —

To all whom it may concern:

Be it known that we Sherman S. Jewett and Francis H. Root, of the City of Buffalo, County of Erie, State of New York, have invented a new and original design for the ornamentation of Cooking Stoves, which we designate by the name of the "Oak" of which the following, in connection with the accompanying drawings, is a full, clear, and exact description.

In these drawings Fig. 1st represents the front plate of the Stove with the sliding doors.

The design on these panels consists of a panel (—) in each jam, surrounded by mouldings, the outer one of which (—) is decorated on the inner edge and in the center of the panel is a rosette (—) in light relief.

Along the upper edge of this plate is a band — enriched with foliage. In the center of each sliding door panel is a twig of oak — with single leaf and acorns on the leaf, and these panels are surrounded by a plain moulding —

The inner edge of each door is ornamented by a vertical band — enriched in the same style as that on the frame.

The side plates represented in Fig. 2^d contains two furnace doors and an oven door. The upper edge is ornamented by a band — similar to the one on the front plate. A cable band — in relief with the spiral grooves — beaded, ornaments the lower edge of the plate, and at the rear end is an elongated panel rounded at the ends. —

In the center of this panel, are two spires in relief, pointing in opposite directions, and separated by an ovate boss, and at the ends is a spear with the point toward the center, and the handle is surrounded by a sheaf of long narrow leaves curved outward at the point forming a cup.

In the center of the panel of the upper furnace door is an oak twig with a leaf and acorns on either side, while in the center of the door below is a single oak leaf, all of which are in relief.

Dec. 1095

The oven door is ornamented by two large leaves pointing in opposite directions, with small leaves between them, all radiating from a common center, and this center is covered by a single acorn. All the doors are paneled, and surrounded with mouldings.

Having thus described our ornamental design for a Cooking Stove what we claim as new and desire to secure by letters patent is,

The ornamental configuration and design for the plates of a stove, as herein described and shown in the accompanying drawings.

In testimony whereof, we have subscribed our names

Witnesses.
